UNITED STATES PATENT OFFICE.

JOHN A. GROVER, OF COLORADO SPRINGS, COLORADO.

MERCHANDISE-DISPLAY TABLE.

1,412,207.

Specification of Letters Patent. Patented Apr. 11, 1922.

Application filed October 20, 1919. Serial No. 331,936.

To all whom it may concern:

Be it known that I, JOHN A. GROVER, a citizen of the United States, residing at Colorado Springs, in the county of El Paso 5 and State of Colorado, have invented certain new and useful Improvements in Merchandise-Display Tables; and I do hereby declare the following to be a full, clear, and exact description of the same, reference being had to the accompanying drawings, forming part of this specification.

This invention relates to mechanical means for presenting merchandise to a customer, particularly such articles as rugs which, in 15 the larger sizes, are quite awkward to handle, but which the customer always desires to see fully displayed, in order to get the "effect" of the rug.

The principal object of this invention is to 20 provide means for displaying a series of rugs of any size conveniently, easily and quickly, and permitting each rug to be displayed at an angle near to that at which it will be used (horizontal),—this in 25 distinction to the present methods of display, which, as far as I am aware, always display the rugs in vertical position, which is often unsatisfactory to the customer, since the coloring of the rug is materially altered 30 at times by the angle the light makes with the nap, this being particularly true in the higher priced rugs where the satisfaction of the customer is most desired by the seller.

A further object of the invention is to 35 provide mechanism so that a number of rugs may be connected together and displayed to the customer one after the other, such mechanism including means for causing the series of rugs to pass either forwardly or 40 backwardly at will and also to regulate the speed of travel of the rugs so that the display will move at the same rate of speed in spite of the constantly increasing diameter of the rugs on the driving roll.

45 A number of other objects of the invention will be apparent upon reading the detailed specification following and particularly as pointed out in the claims.

In the usual rug exhibitors now on the market, the rugs are suspended from huge 50 frame-works, usually pivoted about a heavy central pivot which requires substantial journals on both the floor and ceiling, and in addition normally requires heavy bracing, due to the fact that it is not infrequent during the exhibition of the rugs to have all of them on one side of the pivot, making great 55 stress on the trunnions. It has been suggested heretofore that it would be advisable to display the rugs in horizontal position, 60 but up to the present time no successful attempt has been made to do this, all of the mechanism in kindred arts requiring substantial modification to meet the requirements of this work and presenting obstacles 65 which have not heretofore been overcome. As will be seen from the drawings accompanying this specification, the present device exhibits the rugs in a nearly horizontal position and in the refinements of the machine obviates all of the difficulties incident 70 to such horizontal display.

In the drawings.—

Figure 1 is a side elevation of the complete device showing the relation of the operating mechanism to the display shelf.

Fig. 2 is a plan view of the driving mechanism.

Fig. 3 is a side elevation of such driving mechanism.

Fig. 4 is a vertical section taken on the line 4—4 of Figure 2 looking in the direction of the arrows.

Fig. 5 is a side view of one of the rug connectors.

In its entirety, this rug display device consists in a pair of casings housing the operating mechanism and providing journals for the two rolls on which the series of rugs are wound, and in an extended shelf adjustable as to length over which the rugs pass for display when being wound from one roll to the other. As best seen in Fig. 1, the rugs desired for display are connected together end to end, each rug of the series being of the same or approximately the same

width, by any desired form of connection either by sewing or fastening together with loops of thread, or preferably by hinges made of two arc-shaped sheets of metal 5 curved at a radius equal to the radius of the outer rug when the series of rugs is about evenly divided between the two rolls, each sheet having a hook whereby the rugs are hooked. Such a connection provides great 10 flexibility and causes no wear on the rugs such as would be produced by the more usual forms of fastenings. The last rug of the series is then fastened in the same, or a similar way, to a web of strong serviceable 15 material, such for example as an end of carpet tacked to the axle 10 of one of the rolls and all of the rugs then wound upon such roll. The rugs are then passed upwardly over the small guide roll 11 and 20 then beneath a similar roll 12, directing the rugs over the shelf 13 of the display rack denoted as a whole by 14. At the lower or front end of the display rack is a guide roll 15 directing the rugs back to the axle 16 of 25 the other winding roll, the end rug of the series being fastened to this roll in the same manner as has been described in connection with the axle 10 of the upper roll.

It is preferable in the larger sizes to assist 30 in the guiding of the rugs from roll 15 to axle 16 by having a supporting belt such as 17 carried by the rolls 18 and 19 and driven by means of a sprocket wheel 20 on the shaft of roll 19 driven by a chain 21 passing over 35 a driving sprocket wheel 22 on the shaft of the roller 15. It is also preferable to have the display rack extensible as indicated in Fig. 1, but no specific description of this feature is considered necessary, since this 40 forms no part of the invention and is old and well known per se, although possibly novel in this connection. The axles 10 and 16 are supported respectively by split journal blocks 23 and 24 supported on a heavy 45 beam 25 diagonally arranged in each casting, and these axles, beyond such split journal blocks, are provided with large sprocket wheels 26 and 27 driven respectively from pinion sprocket wheels 28 and 29 by chains 50 30 and 31.

The operating mechanism for these rolls is rather compact in form and forms a very essential portion of the present invention and is best shown in its entirety in Fig. 2 55 which, for ease of description, is spoken of as a front elevation, but as will be noted from Fig. 1 just described, this mechanism is for convenience in operation and also to take up as little floor space as possible, arranged at an angle of about 45 degrees so that the part denoted as "up" is not vertically upward, but actually slants upwardly and backwardly, with respect to a person viewing the display.

65 Sprocket wheel 28 heretofore mentioned

is mounted on a shaft 32 journaled in bearings 34 (Fig. 2) carried by an intermediate cross piece 35 and by a similar front cross piece 36, and is held against longitudinal movement by a shoulder or by any other 70 usual means. Just inside of the front cross piece 36 this shaft carries loosely a gear wheel 37 having a clutch hub 38 connected thereto, the latter co-operating with an ordinary tapered clutch 39 feathered to the 75 shaft 32 which at this portion is cylindrical but is threaded as at 40 from beyond the limit of motion of the clutch 39 to a point near the inward journal 34.

Sprocket wheel 29 is carried by a shaft 80 42 hereinafter called the lower driving shaft and is associated with mechanism exactly similar to that just described in connection with upper driving shaft 32, these elements consisting in the journal boxes 44, loose 85 gear wheel 47 with its hub 48, and the jaw clutch 49 feathered to the shaft 42, and slideable thereon into and out of engagement with the hub 48. One difference, however, in these two mechanisms lies in the fact 90 that the threads 40 on the upper driving shaft 32 are cut right handed while the similar threads 50 on the lower driving shaft 42 are left handed, the purpose of this being that when the nuts 51 and 52 are 95 moved by these threads when the device is in operation, they will both travel in the same direction with respect to the front of the machine, as will be more fully herein-after set forth.

100 Power for the operation of the device is provided by an electric motor 53, or any other means, mounted in a cradle 54 in the rear of the operating mechanism framework, and carrying on its armature shaft 55 105 a worm 56 meshing with a worm gear 57 secured to the shaft 58 which carries feathered thereon a relatively small friction pinion 60 110 slideable up and down the shaft 58 from the top of the framework to the center of the co-operating friction disk 61 driven thereby.

115 This friction disk 61 is a relatively large wheel and is secured to a central shaft 62 journaled in the block 63, next to the disk 61 and supported at its other end by a thrust bearing preferably of the ball bearing type, including a spring 64 which maintains the disk 61 constantly in contact with the friction pinion 60 (see Fig. 2), except when such disk has been manually moved away 120 from such pinion against the force of the spring 64 by means of the fork 66 which may be operated by the foot lever or pedal 67, shown in Fig. 1. At its front end center shaft 62 carries a small wide-toothed pinion 125 68 keyed thereto and constantly in mesh with the two gear wheels 37 and 47 which, as will be remembered are loose on the driving shafts 32 and 42.

130 The two clutches are controlled by a lever

70 centrally pivoted and carrying on either side of such pivot, connections with rods 71 and 72 carrying on their threaded extremities, the usual forks 73 and 74, for operating 5 respectively the upper and lower clutches 39 and 49 depending upon the angular position of the lever 70. One way of controlling the clutching in of one of the clutches and the release of the other is by means of the 10 hand lever 75 rigidly secured to the lever 70 and having a hand grip 76 connected by means of a rod 77 to a lever 78 pivoted to the hand lever 75 at its lower end, so that operation of the hand grip 76 withdraws 15 the bolt 80 from one of the notches 81 of the retaining arc 82, so that the lever 70 may be moved about its pivot and alter the clutching of the two clutches mentioned.

The more usual method of controlling the 20 direction of the travel of the series of rugs, is, however, an automatic means consisting of a cam wedge 83 carried by nut 51 on the upper driving shaft 32 and by a similar but reversed cam 84 rigidly secured to one 25 end of the small shaft 85 sliding in the frame work at its inner end and having its outer pivoted end carried by the nut 51 and by the forked-end bracket 86 sliding on one of the end pieces of the frame work which 30 thereby prevents rotation of the nut 51, although offering no material obstacle to its longitudinal movement. On either side of a block 87 pivoted to the lever 70 and slidably receiving the shaft 85 are springs 90 and 91, 35 resting loosely on the shaft 85 and adapted to be compressed between the plate 92 which carries the cam 84, and the block 87; and between the bracket 86 and such block 87, respectively.

40 Plate 92 which carries the cam 84 is held to shaft 85 by a set screw which allows the adjustment of plate 92 along shaft 85 to any point. This being necessary when a rug is added or removed.

45 When the series of carpets is being wound upon the rolls the nut 51 will be carried by the right handed threads 40 toward the friction disk 61, and when the point of the wedge cam 83 strikes the shoulder 93 of the 50 pin 80 it will cam the pin 80 downwardly against the action of the spring 94 until it is withdrawn from the notch 81. Continued motion of the nut 51 and its attached cam 83 will cause the spring 91 to be tightly compressed between the pivoted block 87 and the 55 forward connection 95 of the rod 85 and when the pin 80 is completely released this spring will drive the block 87 toward the friction disk 61 and will consequently turn 60 the lever 70 about its pivot, this action causing the release of the clutch 39 and the throwing in of the clutch 49, thereby changing the direction of travel of the rugs. On the reverse movement of the rugs the nut 51 65 moves in the opposite direction due to the

motion of unwinding the rug which reverses the direction of the threaded shaft 32, by means of the chain 30, and when this nut has reached a point near the forward limit of its travel, the cam 84 will similarly wedge 70 down the pin 80 and the spring 90 will throw the block 87 and with it the lever 70 into position to again reverse the direction of travel of the merchandise being exhibited. It shou'd be noted here that the hand lever 75 75 may be used at any time to reverse the direction so that if a rug which pleases a customer has been passed it merely requires the manipulation of this lever to bring such rug back to central position on the display rack, and when the customer has been satisfied the hand lever is again reversed, causing the previous movement to be continued.

Just to the rear of the friction disk 61 is 85 located a pair of guide rods 96 and 97, the former of which carries a sliding block 98 connected to the nut 51 by means of a link 99, a bell crank lever 100, and an adjustable connection 101 from the latter to the block 90 98, so that when the nut 51 approaches the friction disk 61, the block 98 will be raised.

On the other guide rod 97 is a similar block 102 which is connected in quite a similar manner to the nut 52 by link 103, bell crank lever 104 and the link 105 connecting the latter to the block 102, so that when the nut 52 advances toward the friction disk 61, which by virtue of the fact that it is traveling on left-hand threads will be simultaneous with the advance of the nut 51, the block 102 will be lowered on its guide rod 97, so that the two blocks 98 and 102 will always be working in opposite directions, although these blocks will not travel at the 100 same rate of speed, on account of the operation of the blocks at different speeds, due to the difference in diameter of the material wound on the rolls.

105 In order that there shall be no transverse friction between the pinion 60 and the larger disk 61 the friction pinion 60 has a flat portion 59 on its periphery to allow movement of the pinion 60 along the shaft 58 for a short period at each revolution. The segmental pulley 106 (which may be a cam if desired) is slidably secured on the shaft 58 as is also the friction pinion 60, and a small spring 107 is mounted on the shaft 58 between the pinion and the pulley in order to 110 keep them somewhat separated. The small arc 108 of the segmental pulley is of the same diameter as the major portion of the pinion 60, but the remainder of the pulley 106 is of less diameter than the drive pinion 60 and consequently does not contact with the disk 61. As best seen from Fig. 4 the flat portion 59 of the friction pinion 60 is mounted in angular relation to the portion 115 108 of the pulley 106 so that at all times one 120

125 130 135 140 145 150 155 160 165 170 175 180

or the other of these two wheels is in contact with the disk 61 but these two wheels are never both in contact with the disk 61 at the same time. Since the portions 59 and 5 108 overlap, it will be noted that when the portion 108 is in contact with the disk 61 the drive pinion 60 is perfectly free to be shifted up or down the shaft 58, if not otherwise held. When the pulley 60 is shifted 10 up the shaft the spring 107 is compressed when the part 108 is in contact with the disk 61, and immediately thereafter, the pulley 106 now being free, is urged up the shaft by the spring, this action being repeated 15 at every revolution of the shaft 58 until the drive pinion 60 is released. The drive pinion 60 has an extended hub in which is loosely fitted a non-rotating collar 118 which is held in spaced relation to the 20 pinion 60 and forms the means for shifting the same up and down the shaft 58, a handle 118 preferably integral with the arm of the collar 118 being provided for convenient manual shifting of the drive pinion.

25 Each of the blocks 98 and 102 carries on the side facing the other block a pivoted dog pressed downwardly by a spring 110 against a stop 111 on the block. The dog on block 98 is numbered 112 in the drawing 30 and the similar dog on block 102 is designated 113. A block 116 which extends from guide rod 96 to guide rod 97 and slides on both carries two similar parallel fingers 115 in such position as to lie in the path of 35 movement of dogs 112 and 113. This block 116 is held on either of the guide rods by a set screw 117, by means of which it can be secured in proper place to release either the dog 112 or the similar dog 113, as it reaches 40 the proper height.

Referring now to Fig. 4, it will be seen 45 that these dogs are in position to engage against the forked collar 118 on the pulley 106. On first touching this collar 118, the dogs will rise against the spring 110 by reason of their beveled surface 119, but will later drop into locking position on such collar by means of the rectangular shoulder 120 and will then drag the pulley 106 up 50 the shaft 58 until the dog comes in contact with the finger 115 which will release the collar 118 and will allow the pulley to work back by gravity to its original position.

55 It will be noted that the nearer the pinion 60 is to the center of the disk 61, the faster will be the speed of the rugs. This may be taken advantage of in case, for example, it is desired to exhibit one of the rugs that is 60 known to be somewhere near the inside of the roll. In such a case by raising the dog, 112 or 113, as the case may be, the pinion 60 will work down the shaft 58 until it comes to its original position and it will 65 remain there until the machine is reversed,

consequently bringing the desired rug quickly to view. Should speed control be desired before the machine is reversed, the pinion 60 may be shifted up the shaft 58 by means of the rod 114, this causing the collar 70 118 to catch on one of the dogs.

What is claimed is:

1. In a rug exhibiting device, a display rack, a plurality of rolls journaled in said rack, a plurality of rugs, means for detachably connecting the rugs to each other and to the rolls to form a connected series, a substantially horizontal display shelf, and means for operating one of said rolls to cause the series of connected rugs to pass 80 over said shelf. 75

2. In a rug exhibiting device, a display rack, a plurality of rolls journaled in said rack, a plurality of rugs, means for detachably connecting the rugs to each other and to the rolls to form a connected series, a substantially horizontal display shelf, and means for operating each of said rolls alternately to cause the series of connected rugs 85 to pass over said shelf. 90

3. In a rug exhibiting device, a display rack, a plurality of rolls journaled in said rack, a plurality of rugs, means for detachably connecting the rugs to each other and to the rolls to form a connected series, a substantially horizontal display shelf, and means for operating said rolls to cause said 95 series of connected rugs to pass over said shelf and for automatically reversing the direction of movement of said rugs. 100

4. In a rug exhibiting device, a display rack, a plurality of rolls journaled in said rack, a plurality of rugs, means for detachably connecting the rugs to each other and to the rolls to form a connected series, a substantially horizontal display shelf, means for operating said rolls to cause said series of connected rugs to pass over said shelf and for automatically reversing the direction of movement of said rugs at any chosen 110 point, and manually controlled means for reversing the direction of the travel of the series at will. 105

5. In a rug exhibiting device, a substantially horizontal shelf, a plurality of rolls, an article to be displayed connected to said rolls and passing over said shelf, a guide roll at one end of said shelf, an endless belt for supporting said article between said shelf and one of said rolls. 115

6. In a rug exhibiting device, a substantially horizontal shelf, a plurality of rolls, an article to be displayed connected to said rolls and passing over said shelf, a guide roll at one end of said shelf, an endless belt 125 for supporting said article between said shelf and one of said rolls, and means operatively connecting said guide roll and said endless belt.

7. In an exhibiting device, a pair of rolls, 130

means for driving said rolls, a shelf, a guide roll at one end of said shelf, and means for supporting the article to be exhibited when passing from said guide roll to one of said 5 rolls.

8. In connection with a plurality of rugs, means for fastening the rugs together end to end, and hinged means for displaying such connected series of rugs in a substantially horizontal plane.

9. In a rug exhibiting device, a pair of rollers, a series of rugs secured at either end to one of said rollers, means for winding said series of rugs on either roller at will, and means tending to equalize the speed of travel of the series irrespective of the 15 diameter of material upon either roller.

10. In a rug exhibiting device, a pair of rollers, a series of rugs secured at either 20 end to one of said rollers, means for winding said series of rugs on either roller at will, means tending to equalize the speed of travel of the series irrespective of the diameter of material upon either roller, and means for 25 automatically reversing the direction of travel of the series at a chosen point.

11. In a rug exhibiting device, a pair of rollers, a series of rugs secured at either end to one of said rollers, means for winding said 30 series of rugs on either roller at will, means tending to equalize the speed of travel of the series irrespective of the diameter of material upon either roller, means for automatically reversing the direction of travel of the series 35 at any chosen point, and manually controlled means for reversing the direction of travel of the series at will.

12. In an exhibiting device, a driving 40 disk, a friction pinion for driving said disk, said pinion having a flat portion on its periphery, means for driving said pinion, and means revolving with said pinion for engaging said disk when said flat portion of the pinion is in proximity to said disk.

45 13. In an exhibiting device, a friction disk, a drive shaft, a plurality of members slidably mounted on said drive shaft and adapted to alternately engage said friction disk, automatic means for moving said 50 members longitudinally of said shaft, and manually controlled means for moving said members on said shaft.

14. In an exhibiting device, a plurality 55 of shafts, a gear wheel loosely mounted on each shaft, a clutch splined to each shaft, a right hand threaded portion on one shaft and a left hand portion on the other shaft, a nut on each shaft, a drive shaft, a pinion on said drive shaft meshing with both of 60 said gear wheels, a source of power, gearing connecting said source of power with said drive shaft, said gearing including a friction pinion and a friction disk driven thereby and mounted on said drive shaft, means 65 governing the position of the friction pinion

with relation to the center of the friction disk, and means connecting said nuts with said control means.

15. A drive shaft, a friction disk thereon, a threaded shaft, gearing connecting said threaded shaft with said drive shaft, a nut carried by said threaded shaft, a drive pinion engaging with said friction disk and movable radially thereto, and means governed by the position of said nut on said 75 threaded shaft for altering the position of said drive pinion with respect to the center of said friction disk.

16. In an exhibiting device, a drive shaft, a plurality of threaded shafts parallel 80 thereto, a gear loosely mounted on each of said threaded shafts, a pinion on said drive shaft meshing with both of said loosely mounted gears, means for clutching each gear to its respective shaft, and adjustable 85 means for unclutching one of said gears and for clutching the other of said gears at any chosen point.

17. In a drive mechanism, a friction disk, a friction pinion driving said disk, automatic means for moving said drive pinion radially of said disk, and manually controlled means for altering the position of said pinion without effecting said automatic 90 means.

18. In a rug exhibiting device, a display shelf, means for causing a plurality of connected rugs to pass over said shelf, said means including a friction disk and a friction pinion driving same, means for rendering said friction pinion inoperative, and independent means for withdrawing said friction disk from contact with said friction pinion.

19. In a rug exhibiting device, a display 105 shelf, a plurality of rolls, a plurality of detachably connected rugs connected to said rolls, means for guiding said rugs over said shelf, means for automatically reversing the direction of travel of said rugs, means for 110 manually reversing the direction of travel of said rugs, means for rendering the entire rug moving mechanism inoperative, independent means for rendering a portion of said mechanism inoperative to permit a 115 chosen rug to remain stationary on the display shelf, means for automatically increasing the speed of travel of said series of rugs when in a given direction, and means independent thereof for causing said series of 120 rugs to travel at maximum speed in the same direction without effecting said automatic speed control means.

20. In an exhibiting device, automatic 125 mechanism for causing the article to be exhibited to move forward and then backward for exhibition, means for altering the chosen point of reversal, adjustable means for altering the position of reversal at the other end of the travel of the article, and 130

means independent of each of said means for manually altering the direction of movement of the article to be exhibited at any point in its travel, and additional means independent of each and all of said previously mentioned means for rendering temporarily inoperative said article moving means.

21. In a device for exhibiting a long and narrow article, a roll attached to said article to wind the article thereupon, means for driving said roll, and means to render the speed of travel of the portion of the article being exhibited constant irrespective of the diameter of the article upon said roll.

JOHN A. GROVER.
